UNITED STATES PATENT OFFICE

ROLLAND G. WILLIAMS, OF BRANFORD, CONNECTICUT, ASSIGNOR TO MALLEABLE IRON FITTINGS COMPANY, OF BRANFORD, CONNECTICUT, A CORPORATION OF CONNECTICUT

HIGHWAY-GUARD-FENCE FIXTURE

Application filed October 31, 1929. Serial No. 403,857.

This invention relates to highway guard fence fixtures, and has for its object to provide a very simple and durable fixture of this description and one which may be readily applied to a post.

In the accompanying drawings which form a part of this application

Figure 1 is a front view illustrating the improved fixture applied to a post the latter being broken away—

Figure 2 is a side elevation of the construction shown at Figure 1 with the post broken away lengthwise—

Figure 3 is a section at the line 3—3 of Figure 1—

Figure 4 is a section at the line 4—4 of Figure 3—

Figure 5 is a detailed front view of the base portion of the fixture, and

Figure 6 is a detailed broken view of the hook bolt.

Similar numerals of reference denote like parts in the several figures of the drawing.

1 is any suitable post, and 2 is the base of the fixture whose inner edges are conformed to the shape of the post, as clearly shown at Figure 3, and whose central portion is open, as seen at 3 at Figure 5, for the purpose of accommodating the hook bolt.

On opposite sides of this opening 3 the face of the base portion 2 is provided with concave gutters or recesses 4 for the accommodation of the cable 5, as will be hereinafter explained, and in the upper and lower edges of the opening 3 are notches or gates 6.

7 is the bolt whereby the fixture is secured to the post, and this bolt extends through the post and the projecting end is threaded while the other end of the bolt is formed into a hook shaped head 8 and from the outer face of this head projects a rib 9, which, when the fixture is properly installed, extends within the notches 6 so as to prevent any lateral movement of the bolt and also for

the purpose of properly positioning the latter.

Also, on the inner edge of this head are formed shoulders 10.

When the parts are properly assembled the cable 5 is within the concave recesses 4 and is embraced midway between these recesses by the hook shaped head 8, as clearly shown at Figure 4, and a nut 11 driven on the threaded end of the bolt 7 will cause the cable to be firmly held between the head 8 and base 2.

It is very important that the cable should slip within the fixture when there is a violent impact against it but should not slip under an ordinary swiping contact, and it would never do for the cable to be strained inwardly by the excessive tightening of the nut 11, since this would make a sharp bend in the cable and would probably break some of the strands thereof, and therefore the shoulders 10 are of such length that they will abut the base when the nut 11 has been operated to cause the proper gripping of the cable.

It will therefore be understood that the length of these shoulders is predetermined by the size of the cable or fence strand since it is obvious that a cable of comparatively large diameter would necessitate shoulder portions that are normally closer to the base, while in the instance of a cable which has a comparatively small diameter, it would never do to have the shoulders normally so close to the base that they would contact the latter before the cable was clamped.

What is claimed is:—

1. A highway guard fence fixture, comprising a post, a base having in its face an opening and horizontally disposed grooves on opposite sides of said opening, the latter having notches formed in its upper and lower edges, a bolt threaded on one end and passed through said opening and post and having a rib extending from the outer surface of its head and housed within said

notches when the cable is clamped, the other end of said bolt having a hook-shaped head, a cable embraced between said grooves and head, and a nut driven on the threaded end of the bolt whereby the base is secured to the post and the cable clamped between said base and head.

2. A construction as in claim 1, further distinguished in that shoulders are provided on opposite sides of the bolt head which shoulders abut the base when a predetermined degree of clamping of the cable has been effected.

In testimony whereof I affix my signature hereto.
